RECOVERY OF NAPHTHALENIC HYDROCARBONS

Art C. McKinnis, Long Beach, Calif., assignor to Union Oil Company of California, Los Angeles, Calif., a corporation of California

Filed Jan. 13, 1961, Ser. No. 82,496
9 Claims. (Cl. 260—674)

This invention relates to the recovery of naphthalenic hydrocarbons from mixtures comprising the same, and in particular concerns a method of treating hydrocarbon mixtures boiling within the 390°—520° F. range and containing naphthalene and/or alkyl-substituted naphthalenes for the purpose of recovering said naphthalenic hydrocarbons in concentrated form.

The expanding use of naphthalene and alkyl-naphthalenes for the production of dicarboxylic acids useful in manufacturing synthetic resins and fibers has created considerable interest in the recovery of these naphthalenic hydrocarbons from hydrocarbon fractions of petroleum origin. It is well known that certain fractions obtained from certain petroleum refining operations, e.g., catalytic cracking and reforming, contain considerable quantities of naphthalene and alkyl-naphthalenes. However, such fractions also contain large quantities of other hydrocarbon types which have boiling points very close to those of the aforesaid naphthalenic hydrocarbons or which form azeotropes therewith. In either case, satisfactory separation of the naphthalenic from the non-naphthalenic hydrocarbons cannot be accomplished by fractional distillation. Other conventional separation techniques, e.g., fractional crystallization, solvent extraction, selective complexing, etc., are equally unsatisfactory for use on a commercial scale.

Accordingly, the principal object of the present invention is the provision of an improved method for treating hydrocarbon mixtures boiling within the 390°—520° F. range and comprising naphthalene and/or alkyl-naphthalenes to separate said naphthalenic materials from non-naphthalenic hydrocarbons present in the mixture. Other and related objects will become apparent to those skilled in the art as the description of the invention proceeds.

I have now found that the above objects and attendant advantages may be realized in an azeotropic distillation process in which N-methyl-formamide (HCONHCH_3) is employed as the azeotrope-former. More particularly, I have found that N-methylformamide forms azeotropes of unusually low boiling point with non-naphthalenic hydrocarbons boiling within the 390°—520° F. range, so that by admixing N-methyl-formamide with a mixture comprising naphthalenic and non-naphthalenic hydrocarbons boiling within said range, and subjecting the resulting mixture to distillation, an exceptionally efficient separation of the two types of hydrocarbons can be achieved. The non-naphthalenic hydrocarbons distill overhead in the form of low-boiling azeotropes with the N-methyl-formamide, leaving the naphthalenic materials behind as distillation bottoms. The azeotropic distillate is rich in hydrocarbons and has a relatively low heat of vaporization, so that the amount of heat required to separate a unit volume of non-naphthalenic hydrocarbons from the feed mixture is relatively low. Also, N-methyl-formamide is but slightly miscible with aromatic hydrocarbons, so that in many instances substantially complete separation of the azeotrope-former from the distillate can be achieved by simple gravity settling. In addition, N-methyl-formamide is essentially non-corrosive and has good thermal stability, and the azeotropic distillation process of the invention is hence not complicated by corrosion or decomposition difficulties.

The process of the invention thus consists in distilling a

2

hydrocarbon feed mixture comprising naphthalenic and non-naphthalenic hydrocarbons boiling within the 390°—520° F. range in the presence of sufficient N-methyl-formamide to vaporize a substantial proportion of the non-naphthalenic hydrocarbons together with the N-methyl-formamide as a minimum-boiling azeotropic distillate, thereby producing an azeotropic bottoms product in which the ratio of naphthalenic to non-naphthalenic hydrocarbons is substantially higher than the ratio thereof in the feed mixture.

Considering now the invention in greater detail, the feedstock to which the distillation step is applied may be any mixture of hydrocarbons comprising naphthalene and/or alkyl-naphthalenes and at least one non-naphthalenic hydrocarbon which cannot be separated from the naphthalenic component by simple fractional distillation. The term "naphthalenic hydrocarbon" is herein employed to designate a hydrocarbon compound whose molecule contains the characteristic naphthalene grouping:

Conversely, the term "non-naphthalenic hydrocarbon" designates a hydrocarbon compound whose molecule does not contain said grouping. Thus, the non-naphthalenic hydrocarbons which may be present in the feedstock include aliphatic compounds such as dodecane, tetradecane, pentadecane, dodecene, tetradecadiene, etc., naphthenic compounds such as cyclohexylheptene, hexylcyclohexane, dicyclohexyl, etc., benzenoid compounds such as triethylbenzene, dimethyl-propylbenzene, diphenyl, phenyl-xylene, octylbenzene, dimethyl-indane, ethyl-indene, etc., and partially hydrogenated naphthalenic hydrocarbons such as methyl-tetralin, dimethyl-tetralin, dehydronaphthalene, methyl-dihydronaphthalene, methyl-decalin, etc. The naphthalenic hydrocarbons which may be present in the feedstock include, naphthalene, the methyl-naphthalenes, the dimethyl-naphthalenes, the ethyl-naphthalenes, the isopropyl-naphthalenes, etc.

The feedstock may be derived from any source, e.g., from products obtained by the destructive distillation or hydrogenation of coal, from products obtained in the processing of shale oil, or from various products obtained in petroleum refining. Usually, however, the feedstock will be of petroleum origin. Suitable petroleum hydrocarbon fractions include catalytically and thermally cracked cycle oils, heavy reformate fractions, heavy coker distillate fractions, dealkylated light catalytic cycle oils, etc. The process is particularly well adapted to the treatment of a material obtained by dealkylating heavy reformate fractions. While the feedstock may be one boiling over the entire 390°—520° F. range, it will usually be one boiling over only a selected portion of such range (e.g., a fraction boiling at 450°—470° F. and comprising mono-methyl-naphthalenes, or a fraction boiling 410°—435° F. and comprising naphthalene) and may of course contain some components boiling somewhat below or (less desirably) above said range. The feedstock may also be one which has been pretreated to remove part of the naphthalenic components, e.g., it may be a dealkylated petroleum hydrocarbon reformate fraction from which at least part of the naphthalene has previously been separated by crystallization.

Procedure-wise, the process is carried out as a conventional azeotropic distillation operation, and any of the techniques commonly applied to such type of operation are applicable to the present process. In its simplest embodiment, i.e., batch distillation, the process consists essentially in adding to the feedstock sufficient N-methyl-formamide to form azeotropes with the non-naphthalenic

components, and thereafter distilling the mixture in a reasonably efficient distillation column. The azeotropic distillate is condensed and passed to a separator where the condensate is allowed to separate by gravity into two phases, one of which comprises the non-naphthalenic components of the feedstock containing a small quantity of N-methyl-formamide, and the other of which comprises N-methyl-formamide containing a small quantity of dissolved non-naphthalenic hydrocarbons. Either or both of said phases may be re-distilled or otherwise treated to recover the azeotrope former for reuse. The naphthalenic components of the feedstock are contained in the bottoms fraction which constitutes the desired end-product of the process.

Two further embodiments of the invention are illustrated in the drawing which forms a part of this application and in which FIGURE 1 diagrammatically illustrates a simple type of continuous operation, and FIGURE 2 diagrammatically illustrates a somewhat more complex system. In the interests of simplicity, the various valves, pumps, heaters, reboilers, reflux condensers, etc. which are characteristic of any distillation system have been omitted from the drawing.

Referring now to FIGURE 1, a hydrocarbon feedstock boiling over the 465°-510° F. range and containing about 35 weight percent of alkyl- and dialkyl-naphthalenes and about 65 weight percent non-naphthalenic hydrocarbons which are predominantly aliphatic and naphthenic is introduced into primary distillation column 10 (which may take the form of a 20-80 plate column operated at reflux ratios of 1:1 to 20:1) wherein it is distilled in the presence of N-methyl-formamide introduced into column 10 as a recycle stream through line 12. The azeotropic distillate taken as overhead from the top of column 10 contains about 60 weight percent of N-methyl-formamide and about 40 weight percent of non-naphthalenic hydrocarbons, and the bottoms fraction remaining in the column contains about 90 weight percent of alkyl-naphthalenes and about 10 weight percent of non-naphthalenic hydrocarbons. The bottoms fraction is withdrawn from column 10 through line 14 as the process product, and may be marketed as such or subjected to further purification, e.g., crystallization. The azeotropic distillate is passed from the top of column 10 through line 16 to condenser-settler 18 wherein it is condensed and allowed to separate into two liquid phases. The lower phase contains about 97 weight percent of N-methyl-formamide and about 3 weight percent of non-naphthalenic hydrocarbons, and is returned to column 10 via line 12 as part of the azeotrope-former recycle stream. The upper liquid phase in condenser-settler 18 contains about 95 weight percent of non-naphthalenic hydrocarbons and about 5 weight percent of N-methyl-formamide. In order to recover the latter, the upper phase is passed via line 20 to secondary distillation column 22 wherein it is subjected to simple fractional distillation. The distillate taken overhead from column 22 consists of the 60-40 azeotrope, and will distill off only so long as sufficient N-methyl-formamide is present to form said azeotrope. Since the stream fed to column 22 contains only 5 percent of the azeotrope-former, the distillate will be relatively small in volume, and the bottoms fraction which is withdrawn from column 22 via line 24 will consist of substantially pure non-naphthalenic hydrocarbons. The distillate from column 22 is passed via line 26 to a second condenser-settler 28 wherein it condenses and separates into two liquid phases. The upper phase in condenser-settler 28 has the same composition as that in condenser-settler 18, and is combined therewith and is returned to column 22 via line 20. Similarly, the lower phase in condenser-settler 28 has the same composition as that in condenser-settler 18, and is combined therewith and returned to column 10 via line 12. As will be apparent, this simple system continuously produces

a naphthalenic concentrate containing 90 percent alkyl- and dialkyl-naphthalenes from a feed stream containing only 35 percent of such naphthalenic compounds with essentially no loss of the azeotrope-former and separation of the non-naphthalenic hydrocarbons in substantially pure form.

In the preceding description made with reference to the processing system of FIGURE 1, it will be noted that the non-naphthalenic components of the feedstock 10 were predominantly aliphatic and naphthenic hydrocarbons, and that a relatively good separation of azeotrope-former from hydrocarbons is obtained in condenser-settlers 18 and 28. However, when the non-naphthalenic components of the feedstock comprise a higher proportion of benzenoid compounds, particularly lower alkylbenzenes, such separation will not be so complete, and it may be desirable to make use of a so-called "miscibility reducing agent" to decrease the solubility of N-methyl-formamide in such hydrocarbons, or to reduce the solubility of the latter in N-methyl-formamide. Usually, it is preferred to employ such an agent when the solubility of N-methyl-formamide in the non-naphthalenic hydrocarbons, or vice versa, is greater than about 20 percent. Any non-reactive material capable of reducing the miscibility of N-methyl-formamide and hydrocarbons may be employed as such an agent, and in general such materials will be miscible with N-methyl-formamide and immiscible with hydrocarbons, e.g., water, or miscible with hydrocarbons and immiscible with N-methyl-formamide, e.g., an aliphatic or naphthenic hydrocarbon such as decane or cyclohexane. FIGURE 2 illustrates a processing system in which a miscibility-reducing agent is employed and in which auxiliary equipment is provided for further processing of the recovered naphthalenic hydrocarbons.

Referring now to FIGURE 2, a wide boiling range feed-stock containing naphthalene, methyl-naphthalenes and dimethyl-naphthalenes as naphthalenic components and various other hydrocarbons, including a high proportion of alkylbenzenes as non-naphthalenic components is introduced into primary distillation column 30 wherein it is azeotropically distilled in the presence of N-methyl-formamide introduced into column 30 as a recycle stream from line 32. The distillate, comprising the azeotrope of N-methyl-formamide and the non-naphthalenic components of the feedstock, is taken off the top of column 30 and is passed via line 34 to condenser-settler 36. Prior to the start of operations, sufficient water (e.g., 10 percent by weight of the N-methyl-formamide employed) is charged to condenser-settler 36 to reduce the solubility of N-methyl-formamide in the non-naphthalenic hydrocarbon components of the feedstock to a low value, e.g., below about 10 percent. Consequently, the upper layer which forms in condenser-settler 36 contains less than 10 percent of N-methyl-formamide, in contrast to the 15-20 percent which obtains in the absence of the added water. Said upper layer is withdrawn from the condenser-settler and is passed to secondary distillation column 38 via line 40. Column 38 produces a small overhead stream consisting of the azeotrope, which is returned to condenser-settler 36 via line 42, and a bottoms fraction consisting of non-naphthalenic components of the feedstock which is passed to storage via line 44. The lower liquid layer which forms in condenser-settler 36 consists essentially of wet N-methyl-formamide. It is passed via line 46 to a small distillation column 48. The overhead from column 48, consisting essentially of water, is returned to condenser-settler 36 via line 42, and the bottoms fraction, consisting essentially of N-methyl-formamide, is returned to column 30 via line 32 as the aforesaid recycle stream. The bottoms fraction produced in column 30 consists essentially of the naphthalenic components of the feedstock. It is passed through line 50 to a crystallization operation whereby the naphthalene is separated in solid form. The mother liquor,

consisting of methyl- and dimethyl-naphthalenes, is passed via line 52 to a third fractional distillation column 54 to produce a methyl-naphthalene overhead fraction boiling at about 455°-470° F. and a dimethyl-naphthalene bottoms fraction boiling at about 480°-510° F.

Fraction No. 7, an additional 100 volumes of N-methyl-formamide is added to the still pot. The phases are separated, and the upper phases of certain of the fractions are analyzed for hydrocarbon types. The analyses and details of the distillation are summarized as follows:

Fraction No.	Upper Layer Volume	Lower Layer Volume	Vapor Temp., °F.	Analysis, percent by wt.				
				Aliphatics and Naphthenics		Benzeneoids		
				C ₁₀	C ₁₁	C ₁₂	C ₁₃ +	
1	24.0	16.0	363					
2	23.0	17.0	370					
3	21.0	19.0	372					
4	20.0	20.0	372					
5	19.0	21.0	376	70.9	21.1	8.1		
6	18.0	22.0	378					
7	17.0	23.0	379					
8	19.0	29.0	376					
9	15.0	25.0	381	56.2	29.6	14.1		
10	9.0	31.0	383					
11	2.0	38.0	385					
12	20.0		>385	1.1	15.3	1.2	53.5	24.3
Bottoms				0.0	3.0	0.7	0.6	4.5
							73.5	23.2

The following example illustrate the practice of the invention in its simplest embodiment, and provide a quantitative demonstration of the efficiency with which the subject separation is achieved, but are not to be construed as limiting the invention:

Example I

A catalytically cracked cycle oil (boiling range=408°-520° F.; density=0.85) having the following analysis as to hydrocarbon types:

Percent by weight	
Non-naphthalenics	65
Aliphatics	22
Naphthenics	23
Benzeneoids	20
Naphthalenics	35
Methylnaphthalenes	9.8
Dimethylnaphthalenes	22.2
Others	3.0

is fractionally distilled in a 40-plate Oldershaw column at a 10:1 reflux ratio and in the absence of N-methyl-formamide. The distillate is collected in thirteen fractions of approximately equal volume, and each of said fractions, together with a small bottom fraction, is analyzed for naphthalenic compounds. The analysis is as follows:

Fraction No.	Volume, percent of Feed	Vapor Temp., °F.	Naphthalenics, percent by wt.
1	6.9	428	0.00
2	7.2	442	1.60
3	7.2	448	2.00
4	7.4	457	2.56
5	7.4	464	2.96
6	7.3	471	2.12
7	7.2	480	1.60
8	7.2	483	1.68
9	7.3	491	2.42
10	7.4	495	3.28
11	7.6	498	3.84
12	7.6	500	4.21
13	7.5	504	4.27
Bottoms	5	>504	2.43

It is to be noted that the naphthalenic compounds are distributed more or less uniformly throughout the entire distillate.

Three hundred volumes of the cycle oil employed above is then admixed with 200 volumes of N-methyl-formamide, and the mixture is fractionally distilled in a 40-plate Oldershaw column at a reflux ratio of 10:1. The distillate is collected in 12 fractions of approximately equal volume, and each fraction is allowed to separate into upper and lower liquid phases. After collection of

Example II

25 The processing system employed corresponds to that shown in FIGURE 1, with column 10 taking the form a 50-plate bubble-cap tower and operating at a reflux ratio of 8:1. The feed stream is a blend of bottom fractions obtained in the catalytic cracking and platinum-catalyzed 30 reforming of a naphthenic petroleum fraction, said blend boiling over the range of about 400°-550° F. (true boiling points) and analyzing as follows:

Percent by weight	
35 Paraffins	1.9
Mono-naphthenes	0.8
Poly-naphthenes	1.0
Alkylbenzenes	17.1
Alkyltetralins	20.0
40 Alkylindanes	6.3
Naphthalenes	46.0
Methylnaphthalenes	1.7
Fluorenes	3.2
45 Acenaphthene	
Biphenyls	

The feedstock is continuously introduced into column 10 along with an approximately equal volume of recycled wet N-methylformamide containing about 8 percent by weight of water. The column is operated to produce an overhead stream at a vapor temperature of about 380° F. and a bottoms fraction boiling above about 420° F. The latter fraction is continuously withdrawn from the bottom of column 10 as the process product, and comprises about 95 percent by weight of naphthalene and methylnaphthalenes. The overhead from column 10 is passed to condenser-settler 18 wherein it separates into an upper hydrocarbon layer, comprising about 96 percent by weight of non-naphthalenic components of the feedstock and of about 4 percent by weight of N-methyl-formamide, and a lower wet N-methyl-formamide layer. The latter is returned to column 10 as part of the N-methyl-formamide supply thereto. The upper hydrocarbon layer is withdrawn from condenser-settler 18 and is passed to column 22 which takes the form of a 20-plate bubble-cap tower operated at a reflux ratio of about 5:1. The overhead fraction from column 22 is withdrawn at a vapor temperature of about 380° F., and is passed to condenser-settler 28. The bottoms fraction from column 22 is withdrawn therefrom and is passed to storage as the non-naphthalenic process product containing less than 5 percent by weight of naphthalenic hydrocarbons. The upper layer in condenser-settler 28 is recycled as part of the feed to column 22, and the lower layer, consisting of wet N-methyl-formamide and being essentially

free of hydrocarbons, is returned to column 10 as part of the N-methyl-formamide supply thereto.

Example III

A bottoms fraction of a platinum-catalyzed reformer product (boiling range=385°-440° F.) is hydrodealkylated over a cobalt oxide-molybdenum oxide catalyst to produce a dealkylated product boiling over the range 141-550° F. This product is fractionally distilled to obtain a light gasoline fraction boiling at 141°-401° F., a naphthalene fraction boiling at 401°-438° F., a methyl-naphthalene fraction boiling at 456°-467° F., and a heavy fraction boiling at 493°-550° F. Analysis shows the methyl-naphthalene fraction to contain about 90.5 percent by weight of 1- and 2-methyl-naphthalenes and about 9.5 percent by weight of non-naphthalenic hydrocarbons, presumably alkyltetralins and alkylindanes. This material, together with 20 percent by weight of N-methyl-formamide, is introduced into column 10 of the processing system shown in FIGURE 1, and the distillation is carried out as previously described. The naphthalenic product withdrawn from the bottom of column 10 contains about 98.5 percent by weight of methyl-naphthalenes.

Other modes of applying the principle of my invention may be employed instead of those explained, change being made as regards the materials or methods employed, provided the step or steps stated by any of the following claims or the equivalent of such stated step or steps, be employed.

I, therefore, particularly point out and distinctly claim as my invention:

1. A process for treating a hydrocarbon mixture boiling within the range from about 390° F. to about 520° F., and comprising naphthalenic and non-naphthalenic components which are not separable by simple fractional distillation, which process comprises azeotropically distilling said mixture together with added N-methyl-formamide to vaporize said non-naphthalenic components together with said N-methyl-formamide as a minimum-boiling azeotropic distillate, thereby leaving as azeotropic bottoms a product in which the ratio of naphthalenic to non-naphthalenic hydrocarbons is substantially greater than the ratio thereof in said hydrocarbon mixture.

2. A process as defined by claim 1 wherein said azeotropic distillate is condensed and allowed to stratify in the presence of an added material having the property of reducing the normal miscibility of N-methyl-formamide and said non-naphthalenic components.

3. A process as defined by claim 1 wherein the naphthalenic components of said hydrocarbon mixture include naphthalene and methyl-naphthalenes.

4. A process as defined by claim 1 wherein said hydrocarbon mixture is one obtained by fractionally distilling a product obtained by the catalytic dealkylation of a platinum-catalyzed reformate fraction boiling between about 385° F. and about 440° F.

5. A process as defined by claim 2 wherein said added material is water.

6. A process for treating a hydrocarbon mixture boiling within the range from about 390° F. to about 520° F., and comprising naphthalenic and non-naphthalenic components which are not separable by simple fractional distillation, which process comprises introducing said hydrocarbon mixture into a distillation column together with sufficient added N-methyl-formamide to vaporize said non-naphthalenic components together with said N-methyl-formamide as a minimum-boiling azeotropic distillate; withdrawing said distillate from said column as an overhead stream; condensing said distillate and allowing the azeotropic condensate to separate by gravity into upper and lower liquid phases; returning the lower phase to said column; fractionally distilling the upper phase; condensing the distillate so obtained and allowing the condensate to separate into upper and lower phase; returning the upper phase to the said fractional distillation step; and withdrawing from said distillation column a bottoms fraction rich in naphthalenic components of said hydrocarbon mixture.

7. A process as defined by claim 6 wherein the naphthalenic components of said hydrocarbon mixture include naphthalene and methyl-naphthalenes.

8. A process as defined by claim 7 wherein the said azeotropic condensate is separated into said upper and lower layers in the presence of an added material capable of reducing the normal miscibility of N-methyl-formamide and said non-naphthalenic components.

9. A process as defined by claim 8 wherein the said added material is water.
